CLAIM

The shape and configuration of an end fitting for a rod stiffening component, as shown.

DESCRIPTION

FIG. 1: is a perspective view of an end fitting for a rod stiffening component according to a first embodiment of the present invention;

FIG. 2: is a side view of the end fitting for a rod stiffening component of FIG. 1;

FIG. 3: is a bottom view of the end fitting for a rod stiffening component of FIG. 1; and,

FIG. 4: is a top view of the end fitting for a rod stiffening component of FIG. 1.
